UNITED STATES PATENT OFFICE.

FREDERICK A. BARNES, OF CLEVELAND, OHIO, ASSIGNOR TO THE FOOTE-BURT COMPANY, A CORPORATION OF OHIO.

WASHING AND WRINGING MACHINE.

Application filed September 29, 1922. Serial No. 591,401.

To all whom it may concern:

Be it known that I, FREDERICK A. BARNES, a citizen of the United States, residing at Cleveland, in the county of Cuyahoga and State of Ohio, have invented certain new and useful Improvements in Washing and Wringing Machines, of which the following is a specification.

The present invention relates to power driven washing and wringing machines and particularly to washing and ringing machines of the type wherein the washing is performed by one or more suction cups or bells which are reciprocated vertically and at the same time given a step by step rotary motion around the tub containing the material to be washed, and the wringing is performed by a suitable wringer which may be carried by the frame of the machine. The washing mechanism and the wringer are usually driven by a small electric motor and my invention relates particularly to a machine so driven, but it will be understood that it is not necessarily limited thereto, nor is it as to certain aspects limited to the specific type of washing mechanism referred to above.

The object of my invention is to provide an improved washing and wringing machine and for a consideration of what I believe to be novel and my invention, attention is directed to the accompanying description and the claims appended thereto.

In the drawing, Fig. 1 is a vertical sectional view of a machine embodying my invention, the section being taken on line 1—1, Fig. 2; Fig. 2 is a plan view of the machine with the tub removed and certain parts broken away to illustrate those below; Fig. 3 is a detail sectional view taken on line 3—3, Fig. 2; Fig. 4 is a detail sectional view taken on line 4—4, Fig. 3; Fig. 5 is a detail sectional view taken on line 5—5, Fig. 1; Fig. 6 is an enlarged detail view of certain parts, and Fig. 7 is a sectional view taken on line 7—7, Fig. 1.

Referring to the drawing, 10 indicates a housing or casing which is entirely closed and which contains the operating mechanism of the machine. In the top of housing 10 is a larger opening 11 of somewhat irregular outline as shown in Fig. 2 and a smaller circular opening 12. Opening 11 is defined by an upwardly-projecting neck 13 surrounded by a flange 14 having a flat

top surface. Housing 10 is provided at one side and adjacent its top with an outwardly-projecting portion 10^a having an opening 15 in its top wall defined by a thickened sleeve 16. Opposite opening 15 the bottom wall 60 of portion 10^a is provided with a thickened section 17 in which is a recess 18. Directly beneath thickened section 17 is a leg 19 of the machine. Leg 19 is formed integral with the bottom wall of portion 10^a and 65 thickened section 17 and is joined to the main housing wall by webs 20. Journaled in recess 18 is a stub shaft 21 which carries a worm wheel 22. Stub shaft 21 has an axial opening in which is fastened the lower 70 end of a vertically-extending wringer shaft 23, the parts being fixed together by a key 23^a. The lower wall of housing 10 at its central portion is dished inwardly as indicated at 24 and is provided with a pedestal 25 75 having a socket 25^a in which is supported the lower end of a stationary shaft 26, the end of the shaft having threaded engagement with the bottom of the socket as indicated at 26^a. Mounted on shaft 26 is a sleeve 80 or shaft 27 which extends the entire length of the shaft and is adapted to turn thereon, the sleeve being held between the top surface of pedestal 25 and a head 28 on shaft 26. On the lower end of sleeve 27 is a cylindrical cam 29 which is preferably formed integral therewith and has a continuous outwardly-facing groove 30 which forms a cam track. On sleeve 27 just above cam 29 is a sliding clutch member 31. It is keyed to the 85 sleeve so it turns therewith and can move vertically on the sleeve between a lower shoulder 32 and the under surface of a worm wheel 33. Worm wheel 33 rests against a shoulder 34 on sleeve 27 and can turn freely 90 thereon. Clutch member 31 has one or more upwardly-projecting pins 35 adapted to enter openings 35^a in the web of worm wheel 33. When in the position shown in Fig. 1 of the drawing it will be seen that the 100 clutch member connects worm wheel 33 to sleeve 27 while when the clutch member is moved downward against shoulder 32, pins 35 are withdrawn from openings 35^a and the worm wheel can turn freely on sleeve 27. 105 Keyed to sleeve 27 above worm wheel 33 is a hub 36 having a locking segment 37 and an arm 38 which carries an actuating pin 39.

At the right hand side of housing 10 110

and in line with smaller opening 12, the housing wall is shaped to provide a vertically-extending guideway 40 which is nearly a complete circle in cross section as shown in Fig. 5, there being a vertically-extending slot 41 which faces toward the center of the housing. In the inner surface of guideway 40 are a number of spaced vertically-extending keyways 42 which terminate short of the top of the guideway as indicated at 43. At its upper end guideway 40 is provided with an enlarged head 44 which provides a shoulder 45 and mounted in head 44 and on shoulder 45 is a hub 46 to which is fixed a stop index wheel 47. Hub 46 can turn freely in head 44 and is provided on its inner surface with keyways 48 of the same size and number as keyways 42. Stop index wheel 47 is provided in its periphery with spaced actuating slots 49 adapted to be engaged by actuating pin 39 and with locking grooves 50 adapted to receive locking segment 37. Slots 49 have the same angular spacing as do keyways 42 and 48. Projecting into housing 10 through smaller opening 12 is a plunger rod 51 having a collar 52 pinned to its lower end which collar serves as a support for a sleeve 53 mounted on the plunger rod. At its lower end sleeve 53 is provided with integral keys 54 which slide in keyways 42 and with a pin 55 which projects through slot 41 and carries a roller 56 which runs in cam groove 30. Pinned to plunger rod 51 just above sleeve 53 is an indexing collar 57 having integral keys 58 which run in keyways 42 and are adapted to enter keyways 48. Sleeve 53 is held between collars 52 and 57 so it cannot move vertically relatively to rod 51, the rod being, however, free to turn in sleeve 53. Opening 12 is provided with a suitable stuffing box for rod 51, the same being shown as comprising a plug 59 which fits opening 12 and is provided with a counterbored opening into which screws a nipple 60 for compressing a gasket 61 around rod 51. Both the plug and the nipple have flanges which serve to divert any water which may fall on them so as to prevent its entering housing 10.

Housing 10 is shaped to provide a projecting portion 62 to accommodate wheel 47 and just below this is a cylindrical extension 63 having a flange 64 to which is bolted a flange 65 on the casing of an electric motor 66. Between flanges 64 and 65 is an insulating ring 67 and surrounding the fastening bolts 68 are insulating sleeves 69 so that the motor casing is entirely insulated from housing 10. Insulating ring 67 is provided with an extension 67^a which forms a dam to keep oil from getting to the motor. In extension 63 is a web 70 which forms a support for a bearing 71 and on the opposite side of the housing is a sec-

ond support 72 for a bearing 73. Web 70 is provided with a drain opening 70^a. Mounted in bearings 71 and 73 is a shaft 74 which is connected to the shaft of motor 66 by a slip coupling 75. Slip coupling 75 may be of any suitable structure and is preferably insulated from shaft 74. Its function is to protect the motor and the machine by slipping in case of overload on the machine. Mounted on shaft 74 is a worm 76 which meshes with worm wheel 33 and a worm 77 which meshes with worm wheel 22. Formed integral with worm 76 is a thrust collar 78, between which and a ring 79 which loosely surrounds shaft 74, are balls 80. Ring 79 binds against the end of bearing 73 so that the ring is held from turning. This forms a ball thrust bearing to take the axial thrust of shaft 74. Formed integral with housing 10 are two radially-extending arms 81 at the outer ends of which are supporting legs 82 preferably formed integral with arms 81. There are thus provided three legs for the machine spaced 120° apart. Arms 81 are each provided with pads 83 which lie in the same horizontal plane as does flange 14 and resting on these pads and flange 14 is a circular cover plate 84 having a downwardly turned, rolled edge 85. Cover plate 84 is fastened to pads 83 by bolts 86 and to flange 14 by a ring 87 which conforms to the outline of opening 11 and is fastened in place by bolts 88. This serves to form a tight cover for opening 11 to prevent the entrance of any water into housing 10. Cover plate 84 has an opening 89 in it to lighten the structure. Fixed at its lower end in opening 15 is a frame tube or post 90 and over each leg 82 is a frame tube or post 91. The upper ends of the frame tubes 90 and 91 serve to support a top ring 93, which is attached to them in any suitable manner. The lower ends of tubes or posts 90 and 91 are suitably attached to the rolled edge 85 of plate 84. The tubes or posts 90 and 91, top ring 93 and cover plate 84 thus form a frame in which tub 94 is mounted. Wringer shaft 23 extends through tube 90 and at its upper end is provided with a coupling member 93^a by means of which it is coupled to the driving mechanism of a wringer. The particular wringer structure forms no part of the present invention and hence is not illustrated. It will be understood that any suitable wringer may be used and preferably it will be pivoted on top of tube 90 so it may swing in a horizontal plane and will be provided with a suitable reversing gearing so it may be run in either direction, this being a known wringer arrangement. It will be noted that the wringer is mounted directly over leg 19 so it has a firm support, the weight being taken by housing 10.

Mounted in the frame formed by posts 90 and 91 and ring 93 is a tub 94 having a cover plate 95. Tub 94 rests on cover plate 84 and is fastened to it at its center by a tubular post 96. Post 96 has a flange 97 which rests on the bottom of the tub and an extension 98 which projects through holes in the tub and cover plate and is threaded on its end to receive a nut 99 to clamp the tub to the frame and the post in position. This arrangement serves to firmly clamp the tub to housing 10 and provides a tight joint at the point where post 96 passes through the bottom of the tub.

Plunger rod 51 extends up through post 96 and carries on its upper end a yoke 100. At the ends of the arms of yoke 100 are mounted suction cups or bells 101 which directly perform the washing operation in a well-understood manner. At the upper end of post 96 is a suitable stuffing box 102 to prevent water from leaking down between the post and the plunger rod. On plunger rod 51 is a downwardly-sloping collar 103 which serves as a water-shed to prevent water coming into contact with the top of nipple 60 where plunger rod 51 passes through it. Collar 103 is located at such a point on rod 51 that when the plunger rod is at the bottom of its stroke the collar stands just above the top of the nipple. During the upstroke of the plunger rod collar 103 passes up into post 96. Preferably plunger rod 51 is made in two parts threaded together as indicated at 104 in Fig. 1 and water shed collar 103 is in the form of a washer held between the two parts of the plunger rod. It will be noted that at the point where the end of post 96 passes through the cover plate the housing is provided with a depression 96^a which forms a recess outside the housing for the reception of nut 99. By this arrangement the connection is brought outside the housing so that any leakage down around the plunger rod 51 will fall onto the top of the housing.

Clutch member 31 may be operated in any suitable manner for connecting sleeve 27 to worm wheel 33. In the present instance it is shown as being provided with an annular groove 105 which receives pins 106 on the forked end of a lever arm 107. Lever arm 107 is fixed to the inner end of a shaft 108 journaled in bearing sleeves 109 in the wall of housing 10. On the outer end of shaft 108 is fixed a lever arm 110 which at its free end has an angularly turned gear sector 111. It will be clear that by raising and lowering the free end of arm 110 the clutch member will be thrown out of and into engagement with worm wheel 33. For actuating arm 110 I provide a rod 112 having gear teeth at its lower end which mesh with the teeth on gear sector 111. Rod 112

extends up through adjacent frame tube 91 and is provided at its upper end with a suitable handle (not shown) for raising and lowering the rod. To hold the clutch member in "in" and "out" positions arm 81 is provided with a downwardly-projecting web 113 having a hole in which a spring-pressed ball 114 is located and lever arm 110 is provided with a pad 115 having two spaced, shallow recesses 116 with which ball 114 engages. This forms a yielding means for holding the clutch in either of its two positions.

Housing 10 contains a suitable supply of oil for lubricating the machine, the oil level being indicated at 117 in Fig. 1. Cam track 30 and the moving parts carried by the lower end of plunger rod 51 dip into the oil during operation so they are directly lubricated. For carrying lubricant up to the worms and worm wheels any suitable means may be used. In the present instance shaft 74 is provided at its one end with an impeller 118 which runs in a casing 119, closed by a cover plate 120. The suction opening of casing 119 is connected by a pipe 121 to the oil supply in housing 10. Connected to the discharge opening of casing 119 is a discharge pipe 122 which extends along the top of shaft 74. The end of pipe 122 discharges oil on worm 76 and worm wheel 33 and the pipe is provided with one or more holes 123 which discharge oil to worm 77 and worm wheel 22.

The operation is as follows: The materials to be washed and the water having been placed in tub 94, motor 66 is started by closing its circuit thereby driving shaft 74. Assuming that clutch member 31 is in "out" position worm wheel 33 will be turned idly on sleeve or shaft 27 by worm 76, and worm wheel 22 will be turned by worm 77 thus driving the wringer shaft 23. Wringer shaft 23 is driven continuously whenever the motor is running and may be connected to the wringer mechanism (not shown) in a well-known manner as already referred to. If clutch member 31 is now thrown to "in" position, i. e., to the position shown in Fig. 1, worm wheel 33 will be clutched to sleeve 27 and will rotate it on stationary shaft 26. This will turn cylindrical cam 29 and as the cam groove 30 moves relatively to roller 56 plunger rod 51 will be raised and lowered once for each revolution of the cam. This imparts reciprocating movement to suction cups or bells 101. During all except the extreme upper limit of its reciprocating movement, plunger rod 51 is positively held from turning on its vertical axis by the engagement between the keys on indexing collar 57 and keyways 42. Sleeve 58 is held from turning by the engagement between keys 54 and keyways 42. Also stop index wheel 47 is held stationary by locking segment 37

which lies in a groove 50. When plunger rod 51 reaches the top of its stroke the keys on indexing collar 57 pass out of keyways 42 and enter keyways 48 in hub 46. At this time locking segment 37 leaves the groove 50 in which it has been turning and actuating pin 39 engages the next adjacent slot 49 and turns wheel 47 an angular distance equal to the distance between slots 49. Locking segment 37 then engages in the next groove 50 to again lock the indexing wheel 47. At the time indexing wheel 47 is being turned by pin 39, hub 46 is locked to plunger rod 51 by indexing collar 57 so that the turning of wheel 47 effects a turning of plunger rod 51 and suction cups or bells 101. Keyways 42 and 48 and slots 49 have the same angular spacing so that keyways 42 and 48 are brought into alignment after each turning movement of wheel 47, and are locked there. Since pin 39 and segment 37 turn directly with cam 29, the suction cups 101 will be given a turning movement at the top of each stroke. The extent of this movement depends on the angular spacing of keyways 42 and 48 and slots 49. Preferably I employ an odd number of keyways and slots so that the suction cups in being turned step by step will be brought down each in different places, the vertical paths taken by one cup during a complete revolution of the cups being midway between the vertical paths taken by the other cup. For example, in the present instance there being nine keyways 42 and 48 and nine slots 49, for one cup 101 to be moved through 180 degrees to the position occupied by the other cup, i. e., half way around, would require four and one-half indexing movements which means of course, that on the fourth indexing movement it would be 20 degrees behind the position formerly occupied by the other cup and on the fifth indexing movement it would be 20 degrees beyond such position. This insures that the suction cups in their travel will cover the entire surface of the material being washed.

With the above-described arrangement it will be seen that the suction cups are positively locked against turning movement during all their strokes except at the upper end thereof when they are released and positively turned through a definite angle. By this arrangement it is insured that the suction cups are only turned when they are above the water line in the tub thereby doing away with the possibility of the cups setting up a revolving of the clothes in the tub and wrapping of the clothes around central post 96.

The use of a cylindrical cam for effecting reciprocation of the plunger mechanism is of advantage in that its use results in a very simple mechanism which is easy to build and not likely to get out of order. Also by shaping the cam variable speed can be

imparted to the suction cups during their reciprocating movements. For example, the cam may be so shaped that the suction cups approach the water slowly on their down stroke and then speed up to force the air in the cups through the clothes, or it may be shaped to produce other variations in speed such as may be found desirable.

The provision of separate worms 76 and 77 for driving the washing mechanism and the wringer respectively is of advantage in that it provides for direct drive for the wringer shaft 23 without the interposition of bevel gearing. This is important because the maximum power is used in operating the wringer, the washing mechanism requiring but a small amount of power in comparison with the wringer.

It will be noted that all the operating mechanism for the machine is entirely enclosed in housing 10 so it is protected and can be perfectly lubricated. There are no openings in the housing through which leakage of lubricant is likely to occur which permits of putting a supply of oil directly in the bottom of the housing from whence it can be carried to all parts which are subject to wear. The possibility of oil getting to motor 66 is prevented by dam 67^a and any oil that gets into casing extension 63 can run out through drain opening 70^a.

The making of housing 10 and the legs of the machine as one integral structure in which all the operating mechanism is enclosed and supported facilitates manufacture as with multiple spindle drills and similar machines and by the use of jigs and fixtures the housing surfaces can be quickly and accurately machined so that perfect interchangeability of parts is insured and the requirement for any special fitting is eliminated. Also in this arrangement since all the operating parts are arranged in and carried by the housing which in turn is supported directly on the floor practically all the weight is taken off the frame of the machine, no parts being supported on the underside of the frame. All the reactions due to the moving parts are taken by housing 10 and not by the tub or frame. In other words, instead of the supporting parts for the actuating mechanism being carried by the tub and frame, they are all carried by a single housing which also supports the tub and frame.

In assembling the machine, the housing 10 with its supporting legs, which together form a self-contained, self-supporting structure which can be handled as a unit is first taken and the operating mechanism for the machine is assembled therein, including the plunger rod 51. This portion of the machine may be then tested as a unit and all the operating parts properly adjusted. Following this, the frame which includes posts

90 and 91, top ring 93 and plate 84 and which has already been assembled is put into place and fastened to the top of the housing. And, last, the tub 94 is 5 put into the frame and fastened therein by putting tubular post 96 into place and fastening it by nut 99. Thus it will be seen that the machine comprises essentially three parts or units, viz, the housing which is supported by the legs and which contains all 10 the operating mechanism, the frame, and the tub. This arrangement is important from a manufacturing standpoint in that it enables the operating mechanism to be assembled 15 in the housing and tested without having to assemble the whole washing machine. The arrangement also facilitates inspection and repair of the machine in that by removing the tub and the frame, the operating mechanism is exposed and appears in 20 its true operating position. In other words, the operating mechanism can be gotten at without having to remove any of it from the machine.

25 It is important that no water be permitted to find its way into housing 10 as it would tend to emulsify with the oil thus reducing its lubricating qualities. The leakage of water into the housing around plunger rod 51 is prevented by water shed 103 and the flanges on plug 59 and nipple 60. Any water which leaks through stuffing box 102 and runs down the plunger rod will be deflected outwardly by the water shed and 30 the flanges and run off the top of the housing.

35 Certain features disclosed in this application are not claimed herein as they form subject matter of and are claimed in the co-pending application of George E. Randles, Serial No. 591,400, filed of even date herewith and whose assignee is the Foote-Burt Company.

40 In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

45 What I claim as new and desire to secure by Letters Patent of the United States, is:—

- 50 1. In a washing machine, the combination of a tub, a plunger rod which projects through the bottom of the tub, washing means actuated by reciprocation of said rod, a cylindrical cam pivoted adjacent to and at one side of said rod, a member carried by said rod which member engages the cylindrical cam, said rod being free to turn in said member, means for rotating the cam on its axis to impart reciprocating movement to the rod, and means for turning the rod in

said member for imparting a rotary step by step movement to the rod.

2. In a washing machine, the combination of a tub, a plunger rod which projects through the bottom of the tub, washing means on the rod, a cylindrical cam for reciprocating the rod, means for locking the rod against rotary movement except at the upper end of its stroke, and means for rotating the rod through a predetermined angle when released from the locking means.

3. In a washing machine, the combination of a tub, a plunger rod which projects through the bottom of the tub, washing means on the rod, means for reciprocating the rod, a mechanism which is given a periodical turning movement at the upper end of the stroke of the rod, and means for locking the rod to said mechanism at the upper end of its stroke whereby a step by step rotary motion will be imparted to the rod.

4. In a washing machine, the combination of a tub, a plunger rod which projects through the bottom of the tub, washing means on the rod, means for reciprocating the rod, a mechanism which is given a periodical turning movement at the upper end of the stroke of the rod, means for locking the rod to said mechanism at the upper end of its stroke whereby a step by step rotary motion will be imparted to the rod, and means for locking the rod against rotary movement during the other portions of its stroke.

5. In a washing machine, the combination of a housing, legs for supporting it, a tub mounted on top of the housing, a plunger rod which projects from the housing into the tub, a vertical guideway having a plurality of keyways, a key fixed to the rod which slides in said keyways, means for reciprocating said plunger rod, and a member which is periodically rotated at the upper end of the stroke of the rod and has keyways in alignment with the keyways in said guide, the key on said rod passing out of the keyways in said guideway and into the keyways in said member at the upper end of the plunger rod stroke whereby the rod will be given a step by step rotary movement.

6. In a washing machine, the combination of a housing, legs for supporting it, a tub mounted on top of said housing, a plunger rod which projects from the housing into the tub, a vertical guide for the plunger rod, a shaft in the housing, a cylindrical cam carried by the shaft for reciprocating the plunger rod, a gear wheel, means for driving the gear wheel, and a clutch for connecting the gear wheel to the cylindrical cam.

7. In a washing machine, the combination of a tub, a plunger rod projecting through the bottom of the tub, a guideway for the rod having a plurality of spaced keyways, keys on the rod which slide in said keyways,

a member located above the guideway and provided with keyways in alignment with the keyways in the guide, the keys on said rod moving out of the keyways in the guideway and into the keyways in said member at the upper portion of the plunger stroke, means for reciprocating said plunger rod, and means for imparting to said member a turning movement equal to the distance between the keyways when the keys on the shaft are in engagement with the keyways in the member.

8. In a washing machine, the combination of a tub, a plunger rod projecting through the bottom of the tub, a guideway for the rod having a plurality of spaced keyways, keys on the rod which slide in said keyways, a member located above the guideway and provided with keyways in alignment with the keyways in the guide, the keys on said rod moving out of the keyways in the guideway and into the keyways in said member at the upper portion of the plunger stroke, a shaft, a cylindrical cam on the shaft for reciprocating the plunger rod, means for driving the shaft, and means operated by the shaft for imparting to said member a turning movement equal to the distance between the keyways when the keys on the rod are in engagement with the keyways in the member.

9. In a washing machine, the combination of a tub, a plunger rod which projects through the bottom of the tub, a member connected to the rod for reciprocating it, said rod being free to turn in such member, a cylindrical cam, means connecting the cam to said member so that as the cam turns the rod will be reciprocated, means for holding the rod from turning except at the upper end of its stroke, and means for turning the rod through a definite angle when released from the holding means.

10. In a washing machine, the combination of a plunger rod, washing mechanism connected thereto, a sleeve on the lower end of the rod in which the rod is free to turn, a shaft adjacent to the plunger rod, a cylindrical cam carried by said shaft and connected to said sleeve for imparting reciprocating movement to the plunger rod when the shaft is turned on its axis, and means carried by said shaft for turning the plunger rod in said sleeve to impart step by step turning movement to the plunger rod.

11. In a washing machine, the combination of a vertical plunger rod, washing mechanism connected thereto, a shaft adjacent to and parallel to the plunger rod, means for turning said shaft on its axis, means connecting the shaft to the plunger rod for imparting reciprocating movement to the plunger rod when the shaft is turned on its axis, and means connecting the shaft to the plunger rod for imparting step by step rotary movement to the plunger rod when the shaft is turned on its axis.

12. In a washing machine, the combination of a vertical plunger rod, washing mechanism connected thereto, a sleeve on the lower end of the rod in which the rod is free to turn, a shaft adjacent to and parallel to the plunger rod, means for turning said shaft on its axis, a cam carried by the shaft, and a roller carried by said sleeve and engaging the cam whereby the plunger rod will be reciprocated when the shaft is turned on its axis, and means carried by said shaft for turning the plunger rod in said sleeve to impart step by step turning movement to the plunger rod.

13. In a washing machine, the combination of a vertical plunger rod, washing mechanism connected thereto, a shaft adjacent to and parallel to the plunger rod, means for turning said shaft on its axis, a cam carried by the shaft, a roller carried by the plunger rod and engaging the cam whereby the plunger rod will be reciprocated when the shaft is turned on its axis, and means actuated by said shaft for imparting a step by step rotary movement to said plunger rod.

14. In a washing machine, the combination of a unit comprising a housing, legs which are attached to and support the housing, and operating mechanism for the machine assembled in the housing, a second unit comprising top and bottom members and posts connecting them which together form a frame, and a third unit comprising a tub, said second unit being mounted on and attached to the first unit and said third unit being fastened in the second unit, whereby said first unit may be assembled and tested without requiring the assembly of the entire washing machine.

In witness whereof, I have hereto set my hand this 26th day of September, 1922.

FREDERICK A. BARNES.
